MOLDED PULP FRUIT BASKET OR THE LIKE

Richard F. Reifers, New Canaan, and Ronald A. Schelmetic, Bridgeport, Conn., assignors to Diamond International Corporation, New York, N.Y., a corporation of Delaware

Filed Mar. 11, 1965, Ser. No. 84,212

Term of patent 14 years

(Cl. D58—4)

FIG. 1

FIG. 5

FIG. 2

FIG. 4

FIG. 3

FIG. 1 is a side elevational view of a molded pulp fruit basket or the like, showing our new design, the side opposite that shown being the same in appearance;

FIG. 2 is a bottom plan view;

FIG. 3 is an end elevational view, the end opposite that shown being the same in appearance;

FIG. 4 is a fragmentary top plan view; and

FIG. 5 is a vertical sectional view taken on the line 5-5 of FIG. 4.

The broken dash lines in FIGS. 1 and 2 indicate indeterminate length.

The characteristic feature of the design resides in upwardly angled side wall panels having a radiused lower edge connected at adjacent vertical edges by a concave-convex radius terminating in a sharply defined peripheral frame segment which intersects in a linear edge disposed immediately above the concave-convex vertical edges of the wall panels and defines a substantially triangular lip thereabove.

We claim:

The ornamental design for a molded pulp fruit basket or the like, as shown and described.
